TOOTHBRUSH HANDLE

John L. Runckel, Lake Oswego, Oreg., assignor to
Skyline Northwest Corporation

Filed Feb. 2, 1972, Ser. No. 223,057

Term of patent 14 years

Int. Cl. D4—02

U.S. Cl. D4—25

Fig. 1

Fig. 2

Fig. 3

Fig. 4

Fig. 5

Fig. 6

FIG. 1 is a perspective view of a toothbrush handle showing my new design;

FIG. 2 is a plan view thereof;

FIG. 3 is a side elevational view thereof;

FIG. 4 is an end view thereof looking toward the left in FIG. 3;

FIG. 5 is a sectional view thereof taken generally along the line 5—5 of FIG. 3; and

FIG. 6 is a sectional view thereof taken generally along the line 6—6 of FIG. 3.

I claim:

The ornamental design for a toothbrush handle, as shown.
